ELECTRICAL CUTOUT

Roy G. Graham, St. Louis, Mo., assignor to James R. Kearney Corporation, St. Louis, Mo., a corporation of Missouri

Application November 19, 1948, Serial No. 61,097

10 Claims. (Cl. 200—114)

1

This invention relates generally to electrical cutouts of the type adapted to interrupt an electrical circuit upon rupture of a fuse link, which constitutes a part of the output, because of the occurrence of an electrical fault in the circuit in which the cutout is interposed, and more specifically to a housed cutout of this general type the housing of which is provided with a movable door on which is mounted a circuit-completing fuse tube and which door drops to its open position on rupture of the fuse link of the cutout so as to completely remove the fuse tube from the circuit and produce a substantial gap in the circuit, the predominant object of the invention being to provide a cutout of this type which, because of its improved construction and arrangement is capable of performing its intended function in an improved and highly efficient manner.

Fig. 1 is a vertical section illustrating the improved cutout of this invention.

Fig. 2 is a horizontal section taken on line 2—2 of Fig. 1.

Fig. 3 is a fragmentary vertical section taken on line 3—3 of Fig. 1.

Fig. 4 is a fragmentary vertical section taken on line 4—4 of Fig. 1.

Fig. 5 is a fragmentary vertical section taken on line 5—5 of Fig. 1.

Fig. 6 is a fragmentary vertical section taken on line 6—6 of Fig. 1.

Fig. 7 is a horizontal section taken on line 7—7 of Fig. 1.

Fig. 8 is a fragmentary vertical section illustrating the lower portion of the cutout as it appears when the door of the cutout has been released for movement to its open position.

In the drawings wherein is shown for purposes of illustration, merely, one embodiment of the invention, A designates generally the improved cutout of this invention which is intended particularly for use in interrupting circuits carrying currents of relatively high amperages. The cutout A comprises a housing 1 which is formed of porcelain, or other suitable electrical insulating material, said housing being open at its front and being provided with a door 2 which normally closes said open front of said housing and is provided with a hand grip 2' for manually actuating same to open and closed positions when desired. The housing 1 is provided with a hanger structure 3 that is secured to the housing by fastening means 4 and which is adapted to be suitably attached to a supporting structure, a cross-arm B, for instance.

Disposed in the upper portion of the housing

2

1 is an upper contact support 5 which is U-shaped in plan (Fig. 2), the rear, bridge portion of said contact support being arranged in contact with an inner face portion of the rear wall of the housing 1. The upper contact support 5 is secured in place by a pair of stud bolts 6 which are anchored by cement or solder 7 in openings 8 formed in said rear wall of the housing, and nuts 9 are received by the forward, screwthreaded portions of said bolts for securing the upper contact support in place. These nuts 9 serve also to secure to the forward face of the bridge portion of the upper contact support 5 a suitable incoming terminal structure 10, said incoming terminal structure having clamped thereto by clamping bolts 11 and a clamping bar 12 an incoming electrical conductor 13.

The outer portions of the spaced legs of the upper contact support 5 have pivoted therebetween, through the instrumentality of a pivot element 14, the upper contact 15 of the cutout A, this upper contact being U-shaped with its bridge portion at the bottom, and said bridge portion of said upper contact is provided with a V-shaped notch 15' which serves a purpose to be hereinafter set forth. The lower portion of the upper contact 15 is urged forwardly by a torsioned coil spring 16 which is coiled about the pivot element 14 and whose opposite end portions engage pins 17 and 18 supported, respectively, by the upper contact support 5 and the upper contact 15 (Fig. 1). Also, the upper contact has secured thereto by a bolt 19 an electrical conductive clip 20, said clip being attached to a conductor 21 whose opposite end is provided with an electrical conductive clip 22 which is secured by a bolt 23 in electrical contact with a portion of the incoming terminal structure 10 (Fig. 3).

Arranged in the lower portion of the housing 1 of the cutout A is a lower contact support 24 which is shaped as is shown to good advantage in Fig. 1. In other words, the lower contact support 24 is U-shaped in plan and the rear face of its bridge portion contacts with a forward face portion of the rear wall of the housing 1. The lower contact support is secured in place by means of a pair of stud bolts 25 which are anchored in openings 26 formed in the rear wall of the housing 1 by bodies of cement or solder 27, as is shown in Fig. 1, said stud bolts 25 having mounted on their forward, screwthreaded end portions nuts 28. The nuts 28 secure the lower contact support 24 in place within the housing 1, and, additionally, these nuts secure to the forward face of the bridge portion of said lower

contact support an upwardly extended portion 29 of an outgoing terminal structure 30. The outgoing terminal structure 30 is constructed and arranged in accordance with the incoming terminal structure 10, said outgoing terminal having clamped thereto by clamping bolts 31 and a clamping bar 32 an outgoing conductor 33. The lower contact support 24 includes transversely spaced, downwardly and forwardly extended portions 34 which are somewhat hook-shaped at their lower and outer ends, the hook-shaped formation of said spaced portions providing bearing cavities 35 which perform a function to be hereinafter set forth.

Supported for pivotal movement between spaced upper portions of the lower contact support 24 by a pivot element 36 is a lower contact 37, said lower contact being U-shaped in plan with its bridge portion at the rear thereof, and the transversely spaced, forwardly extended legs of said lower contact are shaped as shown to good advantage in Fig. 1 and are provided with notches 38 formed in their lower edges which serve a function to be hereinafter set forth. The forward portion of the lower contact 37 is urged downwardly by a torsional coil spring 39 which is coiled about the pivot element 36 and whose opposite end portions respectively engage a pin 40 supported by the lower contact support 37 and a lower edge portion of the bridge portion of said lower contact, as is shown in Fig. 1. Also, a conductor 41 is provided for conducting electrical energy from the lower contact 37 directly to the outgoing terminal structure 30, this conductor 41 being provided at one end with an electrical conductive clip 42 which is secured in electrical contact with the outgoing terminal structure 30 by a bolt 43, and being provided at its opposite end with an electrical conductive clip 44 which is secured in electrical contact with the lower contact 37 by a bolt 45.

Mounted on the door 2 is a fuse link housing which includes an upper bracket 46 that is tubular in shape and is provided with lateral extensions 47 which receive screws 48 for securing said bracket to the door 2. The fuse link housing includes a tubular structure 49 the upper portion of which is received within the lower portion of the upper bracket 46 and which extends downwardly from said upper bracket to a point located a slight distance above the bottom of the door 2. A lower portion of the tubular structure 49 is seated in a curved cavity formed in a saddle 50 which is secured to the door 2 of the cutout by means of screws 51, and this saddle 50 has secured thereto by screw-threaded elements 52 a hinge member 53, said hinge member having a vertical saddle portion 53' which is provided with a curved cavity in which a portion of the tubular structure is seated. The hinge member 53 is provided with a pair of transversely spaced, rearwardly and downwardly extended arms 54 which are provided at their lower ends with outwardly extending trunnions 55, said trunnions being the outer extended end portions of a shaft 55' and said trunnions being seated in the bearing cavities 35 of the lower contact support so as to support the door 2 for hinging movement to open and closed positions.

Extended rearwardly from upper portion of the hinge members 53 is a pair of laterally spaced extensions 56 which receive therebetween an end portion of a link 57, said link being pivotally connected to said extensions by a pivot element 58.

The opposite end portion of the link 57 is pivotally attached to a latch member 59 through the instrumentality of a pivot element 59', said end portion of said link being disposed between a pair of vertically extended, transversely spaced flanges 60 formed on said latch member, and the pivot element 59' is extended through openings formed through said flanges and through said end portion of said link. The latch member 59 includes an upper, transversely extended bar portion 61 from which is extended downwardly a portion 62, and formed on the rear face of said latch member is an inverted U-shaped flange 63 (Fig. 5). Also, the portion 62 of the latch member 59 is provided with a screwthreaded opening that receives the screwthreaded stem of a binding post 64, said binding post comprising a bolt with which a washer 64' is associated.

Pivotedly attached between the lower portions of the spaced flanges 60 of the latch member 59 is the outer end portion of the short leg 66a of a bell crank lever 66, such pivotal attachment of said short leg of said bell crank lever being obtained through the instrumentality of a pivot element 67. The bell crank lever 66 is supported for swinging movement by the shaft 55' whereon it is disposed between the arms 54 of the hinge member 53 (Fig. 6). The longer leg 66b of the bell crank lever normally extends downwardly slightly and forwardly, as is shown in Fig. 1, so that its forward end portion underlies the lower end of the tubular structure 49, and said forward end portion of said longer leg of said bell crank lever 66 is partially circular in shape, as shown at 66c in Fig. 7, to provide a semicircular 66d which serves a purpose to be hereinafter set forth.

The improved cutout of the present invention includes a fuse link 68 which is arranged within the tubular structure 49 of the fuse housing 46. The fuse link 68 may be provided with a head 68' which is forced against a shoulder within the upper bracket 46 by a suitable screwthreaded cap 69, the fuse link being provided with a fusible section 70 (Fig. 1) which is disposed within the upper portion of the tubular structure 49. When the cutout A is arranged for normal operation the lower portion of the fuse link extends out of the lower end of the tubular structure 49 and engages the rear wall portion of the cavity 66d at the forward portion of the longer leg of the bell crank lever 66 (Fig. 7), said fuse link extending rearwardly and upwardly along said longer leg of said bell crank lever to its rear end and then projects upwardly to the rear face of the latch member 59, where said fuse link is looped about the shank of the binding post 64 and is engaged within the inverted U-shaped flange 63 by the washer 64' so as to securely clamp said fuse link to said latch member.

When the cutout is in its effective position for normal operation, opposed portions of the transverse bar portion 61 of the elevated latch member 59 are seated in the notches 38 formed at the lower edges of the opposed forwardly extended portions of the U-shaped lower contact 37. The latch member 59 is held in its elevated position by the fuse link 68 which engages the forward portion of the longer leg of the bell crank lever, as has been previously explained herein, so as to retain said bell crank lever and the latching member in the positions in which they are shown in Fig. 1, where the door 2 is securely locked in its closed position by engagement between said latching member and said lower contact. When

an electrical fault occurs in the circuit in which the cutout is interposed which is of sufficient magnitude, the fusible section 70 of the fuse link is ruptured. This separates the fuse link and interrupts the circuit, of which the fuse link forms a part, and releases the longer leg of the bell crank lever 66 from the restraint normally imposed on it by the intact fuse link and permits said bell crank lever to swing to the position in which it is shown in Fig. 8. As a result of such movement of the bell crank lever 66 the pivot elements 59' and 67 are lowered with the result that the entire latch member 59 is lowered so as to completely disengage the transverse bar portion 61 of the latch member from the notches 38 of the lower contact 37. On such disengagement of the latch member 59 from the notches of the lower contact the upper portion of the door 2 is forced outwardly by outwardly movement of the lower portion of the upper contact 15 acting in response to force exerted by the torsional coil spring 16, whereupon the door swings outwardly and downwardly about the trunnions 55 to provide a substantial gap in the interrupted circuit. In this connection it is to be noted that the upper bracket 46 is seated in the notch 15' of the upper contact 15.

When it is desired to re-fuse the cutout after its door has dropped open, as explained above, the door assembly is removed from the housing 1 of the cutout by disconnecting the trunnions 55 from the bearing cavities of the lower contact support 24, and a new fuse link is assembled with the door assembly. This is accomplished by removing the cap 69 at the top of the upper bracket 46 and passing the new fuse link downwardly through the tube structure 49 and out of the lower end thereof. The cap 69 is then replaced and the fuse link is drawn into engagement with the lower leg of the bell crank lever 66 so as to move the latch member 59 to its effective position. The door is then replaced in association with the housing 1 of the cutout and said door is moved upwardly and inwardly about the trunnions 55 to its closed position, the inwardly moving transverse bar portion 61 of the latch member 59 engaging the inclined lower edges of the forward, spaced portions of the lower contact 37 so as to raise the forward portion of said lower contact against the force of the torsional coil spring 39 to a sufficient degree to permit upper edge portions of the transverse bar portion of the latch member to enter the notches 38 of said lower contact 37.

The normal current path through the cutout A from the incoming conductor 13 is by way of the incoming terminal structure 10, the conductor 21, the upper contact 15, the upper bracket 46, the fuse link 68, the latch member 59, the lower contact 37, the conductor 41, the outgoing terminal structure 30, and the outgoing conductor 33. Also, if desired, the tubular structure 49 may be comprised of an outer tube 49a of Bakelite, or other suitable electrical insulating material, and an inner tube 49b formed of horn fiber, or other suitable material which is characterized by the ability to give off gas in the presence of the heat of an electrical arc. Thus the presence of an inner tube formed of material so characterized will tend to extinguish any electrical arc which may be produced within the tubular structure 49 on rupture of the fusible section of the fuse link.

I claim:

1. An electrical cutout comprising a housing

formed of electrical insulating material, a door hingedly supported relative to said housing for closing an open portion of said housing, an upper contact and a lower contact arranged in spaced relation within said housing, a fuse link housing mounted on said door, a fuse link arranged within said fuse link housing for electrical connection with said upper contact and extended from the lower end thereof, a movable latch member adapted for latching engagement with said lower contact, means for supporting said latch member from said door for independent movement including an element supported for swinging movement and adapted to impart movement to said latch member, said element being engaged by the intact fuse link to maintain the latch member in a position where it is in latching engagement with said lower contact so as to retain the door in its closed position and said element being released upon rupture of the fuse link to cause said latch member to be released from latching engagement with said lower contact and permit said door to move to its open position.

2. An electrical cutout comprising a housing formed of electrical insulating material, a door hingedly supported relative to said housing for closing an open portion of said housing, an upper contact and a lower contact arranged in spaced relation within said housing, a fuse link housing mounted on said door, a fuse link arranged within said fuse link housing for electrical connection with said upper contact and extended from the lower end thereof, a movable latch member adapted for latching engagement with said lower contact, means for supporting said latch member from said door for independent movement including an element comprising a bell crank lever supported for swinging movement and adapted to impart movement to said latch member, said element being engaged by the intact fuse link to maintain the latch member in a position where it is in latching engagement with said lower contact so as to retain the door in its closed position and said element being released upon rupture of the fuse link to cause said latch member to be released from latching engagement with said lower contact and permit said door to move to its open position.

3. An electrical cutout comprising a housing formed of electrical insulating material, a door hingedly supported relative to said housing for closing an open portion of said housing, an upper contact and a lower contact arranged in spaced relation within said housing, a fuse link housing mounted on said door, a fuse link arranged within said fuse link housing for electrical connection with said upper contact and extended from the lower end thereof, a movable latch member adapted for latching engagement with said lower contact, means for supporting said latch member from said door for independent movement including a link and an element supported for swinging movement and adapted to impart movement to said latch member, said element being engaged by the intact fuse link to maintain the latch member in a position where it is in latching engagement with said lower contact so as to retain the door in its closed position and said element being released upon rupture of the fuse link to cause said latch member to be released from latching engagement with said lower contact and permit said door to move to its open position.

4. An electrical cutout comprising a housing

with said lower contact and permit said door to move to its open position, said pivotally supported spring urged upper contact engaging a portion of said fuse link housing.

10. An electrical cutout comprising a housing formed of electrical insulating material, a door hingedly supported relative to said housing for closing an open portion of said housing, a pivotally supported spring urged upper contact and a lower contact arranged in spaced relation within said housing, a fuse link housing mounted on said door, a fuse link arranged within said fuse link housing for electrical connection with said upper contact and extended from the lower end thereof, a movable latch member adapted for latching engagement with said lower contact, means for supporting said latch member from said door for independent movement including an element supported for swinging movement and adapted to impart movement to said latch member, said element being engaged by the intact fuse link to maintain the latch member in a posi-

tion where it is in latching engagement with said lower contact so as to retain the door in its closed position and said element being released upon rupture of the fuse link to cause said latch member to be released from latching engagement with said lower contact and permit said door to move to its open position, said pivotally supported spring urged upper contact engaging a portion of said fuse link housing which is formed of electrical conductive material.
